CONVEYING APPARATUS

Fred C. Arey, Oak Park, Ill., assignor to Vulcan
Soot Blower Corporation, a corporation of
Pennsylvania

Application April 9, 1938, Serial No. 201,067

1 Claim. (Cl. 198—219)

It is common practice, where small objects, such as small castings and screw machine parts, are manufactured in large quantities, to carry such objects through washing and cleaning apparatus to remove dirt, oil, metal chips and the like. Ordinarily, the objects to be cleaned and washed are carried through the apparatus on a suitable conveyer having work-supporting areas composed of perforated plates through which the washing and cleaning fluids and the dislodged foreign matter on the work can pass. So far as I know, no apparatus of this type has been successful in cleaning objects having therein pockets or recesses in which foreign substances can easily accumulate.

The object of the present invention is to produce an apparatus, of the general type above mentioned, which will make it possible effectively to clean small objects even though they contain open pockets or recesses.

In carrying out my invention, I employ a housing and means for carrying the work through the housing where it is subjected to the action of cleaning, washing and, preferably also, drying fluids. In accordance with my invention, however, the objects are tumbled as they travel through the housing and thus present all of their sides or faces, at one time or another, to the cleaning and drying jets, and the latter are permitted to enter pockets and depressions which, in turn, empty themselves as the objects are turned over.

The various features of novelty whereby my invention is characterized will hereinafter be pointed out with particularly in the claim; but, for a full understanding of my invention and of its objects and advantages, reference may be had to the following detailed description taken in connection with the accompanying drawings, wherein:

Figure 1 is a side elevation of an apparatus embodying the present invention; Fig. 2 is an end view of the apparatus, on a somewhat larger scale than Fig. 1; Fig. 3 is a section, on a vertical transverse plane indicated by line 3—3 of Fig. 4, illustrating on a still larger scale, the upper part of the apparatus; Fig. 4 is a vertical longitudinal section, on a smaller scale than Fig. 3, the plane of the section being indicated by line 4—4 in Fig. 3; Fig. 5 is a bottom plan view of one of the overhead jetting devices; Fig. 6 is a section, on line 6—6 of Fig. 4, but on a larger scale; Figs. 7 and 8 are side elevational views, on the same scale as Fig. 6, showing a fragment of the apparatus with the oscillatory grate ele-

ments in two different positions, the near side wall of the housing being omitted and a portion of the corresponding side wall of the trough through which the work travels being broken away to expose the grate elements.

In the particular apparatus illustrated in the drawings, there is a long tank 1 open at the top. Supported upon this tank is a housing 2 of about the same length, open at the ends and on the under side. The tank is divided into two compartments by a vertical transverse partition 3 and is provided in one of its long side walls with suitable clean out doors 4, one for each compartment.

A horizontal work support extends through the housing, just above the top of the tank, preferably projecting far enough beyond what may be termed the inlet end of the housing, to permit objects to be operated upon to be deposited thereon outwardly from the housing. The opposite end of the work support may project somewhat beyond the housing so that the objects may be discharged upon a conveyer or other receiver, not shown, after their treatment has been completed.

In the arrangement shown, the work support comprises a pair of parallel metal beams 5, 5 in the form of angle bars each having a vertical flange to which is secured an upright plate 6 extending throughout the length thereof and forming the sides of a trough or chute whose bottom is formed by a grate structure. This grate structure comprises a series of rocking sections which not only support the objects to be operated upon, but move them step by step through the housing and turn them over or tumble them as they progress. In the arrangement shown, each grate section consists of a series of segmental plates 7 fixed to a rock shaft extending between and journaled in the longitudinal beams 5; the plates in each unit being arranged with their planes at right angles to the axis of their supporting shaft and being spaced apart from each other a distance somewhat greater than the thickness of a plate. The shaft of each unit extends through the point which is the center of curvature of the curved edge of each plate. Although each grate unit is just like every other unit, except that the plates in half of the units are staggered with respect to the remainder, so that the plates in each unit can enter for some distance into the spaces between the adjacent ends of the plates in the two units between which it lies, one half of the total of rock shafts are indicated by the 55

reference number 8 and the other half by the reference number 9; the shafts 8 and 9 alternating with each other. The shafts 8 are provided with radial rocker arms 10 at one end, 5 while the shafts 9 are provided with radial rocker arms 11 at the ends which are on the opposite side of the apparatus from that at which the arms 10 are located. On the extreme front end of the beams 5 is an electric motor 12 which, 10 through a speed reducer 14 and a sprocket chain drive 15, rotates a transverse shaft 16 positioned below the beams 5. On each end of the shaft 16 is a disk or double crank 17. The rocker arms 10 and 11 extend downwardly from their rock 15 shafts, and those in each group are connected together by a connecting rod, the two connecting rods being indicated at 18 and 19 respectively. The two connecting rods are in turn connected to the disks or cranks 17 by pitmans 20 and 21, 20 respectively, at points which are displaced from each other one hundred and eighty degrees angularly of the shaft 16. The relative lengths of the pitmans 20 and 21 is such that when these pitmans are at the opposite ends of their strokes, 25 the upper edges of the plates of one set of grate units are horizontal while the corresponding edges of the other set make an angle of somewhat more than forty-five degrees to the horizontal. In other words, while the work supporting faces 30 of one half the units are swinging toward a horizontal position, the corresponding faces of the adjacent units are swinging upwardly into inclined positions.

In the use of the apparatus, assuming that 35 the work supporting surface of the first or right-hand grate unit in Fig. 7 is horizontal, and that there is an object A resting thereon, a turning of the shaft 16 in either direction causes the rock shafts 8 to turn in the counter-clockwise direction and the shafts 9 to move clockwise. Thus, 40 the surface on which the object A is resting becomes an inclined surface, the inclination increasing progressively, until the object begins to slide down the incline. During this time the 45 second grate unit from the right in Fig. 7 starts to swing down as to carry its work-supporting surface toward a horizontal plane. The object A, after sliding down on the first grate section, is stopped by the cylindrical surface of the second 50 grate section but, when the limit of oscillatory movements of the grate have been reached, so that the work-supporting surface of the second section has become horizontal, as indicated in Fig. 8, the object A will be found to have been 55 deposited upon the second section; the shifting of the object from one section to the other being usually accomplished in such a manner as to turn the object upside down, or at least to tumble it so that it no longer has the same side facing 60 upwardly as was the case while it was resting on the first grate section. The shifting of a piece of work from one grate section to the next, as just described, occurs during a half revolution of the shaft 16. During the next half revolution, the second and the third grate sections 65 from the right in Figs. 7 and 8, cooperate as preferably did the first and the second sections, so as to cause the object to be delivered from the second grate section to the third. In this 70 way objects dumped on the grate sections lying outwardly from the inlet end of the housing, are fed step by step into and through the housing and are tumbled or turned over during each forward movement. It will be noted that the 75 walls 6 between which the grate units are dis-

posed prevent the objects that are being carried through the housing from falling off at the sides of the grate structure, and compel them to move ahead to the discharge point.

The compartment in the righthand end of the tank, as viewed in Fig. 1, is adapted to contain a hot soda solution or other solvent to cut dirt and grease, while the other compartment is adapted to contain hot, clear rinsing water. As the work travels through the housing, it is subjected first to jets of liquid from the first compartment, then to jets of liquid from the other compartment and, finally to air jets; thus causing the work to be washed, rinsed, and dried before leaving the housing. 15

Two pumps 22 and 24, are provided for pumping the liquid. The inlet side of pump 22 is connected to the washing water compartment of the tank through a pipe 25, while the pump 24 is connected to the other compartment through a 20 pipe 26; both connections being well above the bottom of the tank to permit the settling of solids in a zone below the level at which liquids are withdrawn for use. Discharge pipes 27 and 28 extend from the respective pumps up above 25 the top of the housing and from there extend down into the upper part of the housing. The pipe 27 is shown as terminating in a header comprising three transverse conduits 29 high above 30 the grate device and distributed lengthwise of 35 the housing over the compartment for washing water. The pipe 28 terminates in a similar header. Each of the conduits 29 has at its ends outwardly and downwardly inclined legs 30, 40 which terminate in depending tubular elements 31 lying outside of the walls 6. Each of the tubular elements 31 terminates in a head 32 seated in an opening 33 in the corresponding wall 6 just above the grate device. The under or inner walls of the members 29 and 30 and the inner walls of the heads 32 are provided with jetting orifices 34. Thus, each of these header units, when the pumps are in operation, 45 discharges jets of fluid straight down, diagonally toward the grate device from each side of the latter to the other, and horizontally in both directions across the grate device. In this way cleaning and rinsing liquids are caused to strike each piece of work from five different directions. The liquids, after having done their work, run 50 down between the grate bars or plates into the respective compartments from which they were drawn, and can be used over again. 55

Toward the outlet end of the housing is a third header comprising two of the conduits 29 which 55 are supplied with air under pressure through a pipe 35 entering the housing from above. It is not necessary that the air be discharged in a horizontal direction above the face of the grate and, therefore, the headed tubular members that 60 depend from the other conduits 29 are omitted. 65

The top of the housing contains a number of outlets 36 through which air and vapors can escape. I also prefer to divide the housing into compartments to confine each fluid to a considerable extent in a given zone. In the arrangement shown, there are transverse partition walls 37 in the upper part of the housing, these walls extending downwardly only a short distance. Hanging from the lower end of each of the 70 partitions 37 is a flexible apron 38, conveniently 75 of rubber; these aprons extending into the top of the trough between the walls 6, 6. There is one of these partition devices close to each end of the housing, a third between the first two 75.

headers and a fourth between the second and third header.

The housing is preferably provided with a door opposite each header, preferably on the same side 5 of the apparatus as the clean-out doors 4. In the arrangement shown, these doors, indicated at 39, 40 and 41, are of the vertically slideable, lift type.

While I have illustrated and described with 10 particularity only a single preferred form of my invention, I do not desire to be limited to the exact structural details thus illustrated and described, but intend to cover all forms and arrangements which come within the definitions of 15 my invention constituting the appended claim.

I claim:

In an apparatus of the character described, an elongated housing, a horizontal grate device ex-

tending through the length of the housing; said grate device being composed of a series of units each comprising a rock shaft and flat plates arranged on edge and fixed at corresponding ends to the shaft and spaced apart from each other a distance only a little greater than their thickness, the plate having straight edges located in a common plane approximately radial to the shaft and other edges curved to form a segment of a cylindrical surface extending downward from said plane; the units being so disposed that the ends of the plates in each unit having the curved edges, are entered in the spaces between the ends of plates that are fixed to the shaft of an adjacent unit; and means connected to said shafts to rock alternate shafts in opposite directions. 10 15

FRED C. AREY.
